Primary Examiner — Karen E Kearney(74) *Attorney, Agent, or Firm* — Antonelli, Terry, Stout & Kraus, LLP.(57) **CLAIM**

The ornamental design for a construction machine display with a graphic user interface, as shown and described.

DESCRIPTION

The FIGURE is a front elevational view of a construction machine display with a graphic user interface showing our new design.

The broken line showings of the construction machine display and portions of the graphic user interface are included for the purpose of illustrating environmental structure and portions of the article and form no part of the claimed design.
